United States Patent Office.

ROBERT B. FORBES, OF BOSTON, MASSACHUSETTS.

Letters Patent No. 96,789, dated November 16, 1869.

IMPROVEMENT IN RIGGING SHIPS.

The Schedule referred to in these Letters Patent and making part of the same.

Be it known that I, ROBERT B. FORBES, of Boston, in the Commonwealth of Massachusetts, have invented a new and useful System of Adjusting and Arranging the Sails, Spars, and Rigging of Ships; and I do hereby declare that the following is a full, clear, and exact description of the same and its construction and operation, reference being had to the annexed drawings, which make a part of this specification.

In this drawing the letters represent the different articles in the improvement, viz:

A represents the leading-lines or jack-stays, by which the sails are conducted to their furling or reefing-locality.

B represents the spars attached to sails.

C represents the spaces for the clearance of the stays.

D represents the tackles for manipulating the courses.

E represents the T of lower and top-sail yards.

F represents the slings of lower and top-sail yards.

G represents the downhauls.

H represents the stays.

I, strengthening-bands of sails.

B' represents the spar at the foot of the courses.

The novelty of my invention consists, for the most part, in the following-described devices, employed in rigging what are known as square-rigged ships.

First, in bending or attaching the square sails, each by its foot or longest side, to battens or other usual and convenient means, to the yards next below them, instead of bending, by the head or upper edge, to the yards next above, as is usually done.

Second, the yards, excepting the upper one of all, are slung and parreled to their respective masts; above the eyes of the rigging and back-stays, and above the fore-and-aft stays, instead of below, as is usually done.

Third, the sails thus bent are furled and reefed by being lowered or dropped to or toward their respective yards, and in case of the courses, toward the deck, instead of being raised, as is usually done. They are raised by being triced up by the heads to yards next above, instead of being sheeted home to the yards next below.

Various changes in the usual adjustment and arrangement of spars, yards, rigging, and sails are required to practically apply my said invention.

For example: The lower yards, top-sail yards, and top-gallant sail yards are slung permanently to their respective masts, and do not hoist up and down. The drawings, at E and F, show my system of slinging and parreling these yards to their masts.

The sails are conducted or led to and from the yards whereto they are triced up to and from the yards, where they are bent, or are furled by means of rings, bulls-eyes, or other appliances, running on jack-stays, A, in the drawings, in red ink. These jack-stays are fastened to the yard, one end upon one and the other upon

the other, and arranged to be loosened on the yard, to accommodate the bracing the different yards upon different planes. They may be placed before and abaft the sails, and in heavy ships, I recommend their use in both places. When the tricing-pennants are let go, the sails run down on these jack-stays by means of said rings, to or toward their foot, and are ready for reefing or furling. In hoisting, they are led to their places in the same manner.

On the heads of all the sails thus bent by the foot, and on the heads of the courses, and at the middle thereof, are attached spars, B, of any convenient length, so placed as to allow a space, C, in the drawings, between the yard next above and the said spars, of about one foot. This will permit the bracing the yards without chafing by the stays. Take a piece, of the shape and size required, out of the head of the sail, at the middle, and attach the spar to the sail at the bottom of the space C is produced. Thus the space C is produced.

It will also be best in using my arrangement, to have the masts more nearly plumb than usual, and the stays should lead as nearly horizontal as may be, in view of the adequate support of the masts.

I dispense with the heavy sheets and ties usually required in setting the sails, and also with the heavy foot-ropes which are used when the largest side of the sail is sheeted home by the clews.

At the foot of the courses are attached spars, of nearly the space between the rails abreast of the respective masts; and the courses are lowered to or toward the deck for reefing and furling, instead of being hauled up by clew-garnets or other ropes to or toward their yards.

The use of spars at the foot of the courses I do not claim as new. They have been used before, especially on English coasters; but I do claim the use of them in connection with my said system of reefing and furling and working the courses, by lowering instead of hoisting, and of conducting them on jack-stays.

The tricing-lines whereby my sails are hauled up must be led along the yards toward the slings, so as not to cramp the yards in bracing.

The lower and top-sail yards in my system are hung to the lower masts, and are entirely independent of the pole-masts. In steamers, this is an important feature, as the pole-masts should always be abaft, and ready to house at will. The sails should have a band running from near the middle, at their heads, diagonally to their lower corners. This band is represented at I, in the drawings.

In operation, my system is made to work as follows:

The yards are parreled and slung to the masts by the parrels E, and the slings F, above the eyes of the rigging and back-stays, and above the fore-and-aft stays.

The sails are bent to the yards next below them, and the courses are attached to these spars, both by their foot, and the spars B are attached to the heads of the sails and the courses, so as to make the space C. The stays H afford the usual support, and the tackles D, for manipulating the courses, are made to accommodate the change between my courses and those in use.

If it is proposed to lower the sails or courses for reefing or furling, the tricing-lines are loosened or let go, the downhauls G are drawn upon, and the sails drop down to the point desired, guided by the jack-stays A. On the other hand, to set the sails, the downhauls must be loosened, or the reefing-tackle let go, and the sails drawn up by the tricing-lines to the desired position.

In working this system, it will be seen the top-sails are furled by going no higher than the lower yards, the top-gallant sails by going to the top-sail yard, and the royals, where there is a sky-sail, by going to the top-gallant yards.

In this rigging, I believe the sails will set flatter, and can be more easily taken in, reefed, and furled than in any other. The yards can also be braced much sharper.

On long voyages, in latitudes where fine weather permits, for a long time the heads of the sails can be temporarily bent to the yards at their heads, if desired, and thus the sails on any given mast will more nearly approximate to a single and continuous sheet of canvas. Also, my courses may be hauled up in calms and light winds as usual, if required.

If studding-sails are to be used, the booms must be run in and out along the lower after-quarters of the yards, as is now done in some ships, or directly on top.

There are in this system practically no top-masts, as the top-sails are confined and set upon the lower mast-heads, so that, in effect, the movable masts, fiddled abaft the lower masts, are really pole top-gallant, and royal, and sometimes sky-sail masts, and not pole top-masts. But this mode of arranging masts has been long known, and as, I think, originated with me, as far back as 1843 or 1844.

In my arrangement of the sails, I should recommend that the sails should be convertible to various places, so, also, the yards; that is to say, the main top-sail yard should be of the same length as the fore-yard,

the main top-gallant yard the same as the fore top-sail and the cross-jack yard, the main royal the same as the fore top-gallant and the mizzen top-sail yard, and the sails, although differing in weight, may be used in like manner in various places, but this is not necessary.

It will be observed, that while I dispense with the regular top and top-mast rigging, as commonly arranged, I have mast-head shrouds to do the duty of top-mast rigging more effectually, and I have Jacob-ladders running up from a platform, so that the men may have a landing-place, and also means to go aloft.

It will be seen that the uppermost sail of all in my system must be bent as usual by the head to the yard above.

Claims.

I claim, and desire to secure by Letters Patent—

1. The bending of the square sails of vessels by the foot to the yards next below, in such manner that they can be reefed and furled without starting the foot, and without lowering the yard above.

2. Spars attached to the foot of courses, in combination with courses arranged to reef and furl, as herein described.

3. Slinging and parreling the yards of vessels to their masts above the eyes of the rigging and back-stays, and above the fore-and-aft stays.

4. Jack-stays arranged before or abaft the sails, for conducting them to their positions.

5. The arrangement for reefing and furling sails and courses, without starting the foot, and without lowering the yard above, consisting of yards slung and parreled to the masts above, instead of below the eyes of the rigging and back-stays and fore-and-aft stays, sails bent by the foot, courses attached by the foot to spars, and coming down on deck to furl and reef, and jack-stays for conducting the sails.

6. Attaching spars to the head of the sails bent by the foot.

7. The space C, in combination with square sails, bent at the foot, as described.

R. B. FORBES.
